Filed Apr. 10, 1968, Ser. No. 11,385

Term of patent 14 years

Int. Cl. D3—03

U.S. Cl. D88—3

FIG. 2

FIG. 1

FIG. 4

FIG. 3

FIGURE 1 is a side elevation of the runner.

FIGURE 2 is a top plan view of the runner.

FIGURE 3 is a bottom plan view of the runner.

FIGURE 4 is an end elevation of the runner.

The characteristic feature of the design being the flat-topped head of the T-shaped element; the angular margins at the undersurface of the head and the relationship of the lower rounded end of the cylindrical sleeve (FIGS. 1 and 4) in relation to the appearances afforded by rounded ends of the head relative to the parallel long sides interrupted by the tubular sleeve.

I claim:

The ornamental design for a runner for flat umbrella, as shown and described.
